Harry Kramer, INVENTOR

BY Victor J. Evans

ATTORNEY

UNITED STATES PATENT OFFICE

HARRY KRAMAR, OF NEW YORK, N. Y.

NICOTINE STOPPER FOR CIGARETTE HOLDERS

Application filed June 6, 1928. Serial No. 283,383.

My present invention has reference to a smoker's article, and my object is the provision of a simple, cheaply constructed and thoroughly effective means which is designed 5 to be arranged in the bore of the stem and in the bore of the mouth piece of either a pipe, cigarette or cigar holder, and which means is provided with a chamber for the reception of an absorbent porous element that will serve 10 as a stop and a retarding means for the obnoxious saliva from the wet tobacco as well as a means for preventing vapors from the nicotine and the tobacco entering the mouth of the smoker and consequently insuring a 15 cool, clean, and non-injurious smoke for the user of the device.

To the attainment of the foregoing the invention consists in the improvement as hereinafter described and definitely claimed.

In the drawings:

Figure 1 is a central longitudinal sectional view through a pipe equipped with the improvement.

Figure 2 is a similar sectional view through a cigar or cigarette holder provided with the improvement.

Figure 3 is a perspective view of the improvement with the parts constituting the same separated.

Figure 4 is a central longitudinal sectional view through the improvement.

As disclosed by Figures 1 and 2 of the drawings, my improvement is designed to be arranged in the stem and in the mouth piece 35 of either a pipe 1 or a cigar or cigarette holder 2. In both of these figures the stem of the smoker's article is indicated by the numeral 3 and the mouth piece by the numeral 4. In the bore of the stems 3 there is arranged a 40 tube 5. As disclosed by the drawings this tube has its outer end cut angularly, as at 6, so that this end will, when the device is employed in connection with the pipe 1, rest in the bottom of the smoke chamber of the bowl 45 of the pipe and substantially conform to the

shape of the bottom of the smoke chamber. The second end of the tube 5 is formed with an enlarged cylindrical extension or chamber 7, designed to have telescopically received therein a similar cylindrical chamber 8 formed on one end of a tube 9 that is designed to be received in the bore of the stem 3. The cylindrical enlarged end 8 of the tube 9 is formed with a substantially V-shaped slit and the metal bounded by this 50 slit is bent inwardly to provide a tongue 10. This tongue is designed to be contacted by an absorbent agent 11 such as raw cotton or the like and the said tongue prevents the agent 11 from entering the tube 9. In addition to this 55 the tongue prevents the packing of the raw cotton in the chamber and causes the outer end of such raw cotton or the like to have its end assume an angle at the part thereof contacting with the tongue, so that the smoker 60 is at all times permitted to freely draw the smoke from the bowl of the pipe or through a cigar or cigarette. Also the tongue 10 permits of the ready withdrawal of the absorbent agent 11 should the same become saturated 65 with saliva and the oil from the tobacco.

With my improvement it will be seen that the absorbent agent serves as a stop for any tobacco crumbs, moistened tobacco or nicotine 70 vapor which would otherwise be drawn into the mouth of the user. The device is simple, may be cheaply manufactured and may be readily arranged in the stem and mouth piece 75 of any ordinary construction of pipe, cigar or cigarette holders, to insure a cool and healthy smoke to the user thereof.

While I have illustrated a satisfactory embodiment of my improved device my features of invention are capable of extended application and I do not wish to be restricted to the specific structure herein shown and described.

Having described the invention, I claim:

In a smoker's article, the combination with 90

a stem and a mouth piece connected with the stem, of tubes received respectively in the bore of the stem and in the bore of the mouth piece, each of said tubes at the confronting ends thereof having cylindrical enlargements, one designed to be received in the other, a substantially V-shaped tongue extending angularly into one of said chambers, and providing a stop for an absorbent element which is received in said chamber.

10 In testimony whereof I affix my signature.

HARRY KRAMAR.
